UNITED STATES PATENT OFFICE.

FREDERICK E. PERNOT, OF BERKELEY, CALIFORNIA.

FOG-SIGNAL FOR VESSELS.

1,134,554.

Specification of Letters Patent.

Patented Apr. 6, 1915.

Application filed August 24, 1914. Serial No. 858,242.

To all whom it may concern:

Be it known that I, FREDERICK E. PERNOT, a citizen of the United States, residing at Berkeley, in the county of Alameda and 5 State of California, have invented certain new and useful Improvements in Fog-Signals for Vessels, of which the following is a specification.

The present invention relates to improvements in intermittently operated audible fog signals, and the invention has for its principal objects to provide an intermittently operated signal with a sound deflecting or directing mechanism which will direct the sound issuing from the sounding device in different directions, the variation in volume, owing to the change in direction of projection of the sound, warning approaching or passing vessels of the position 10 of the signal relative thereto, and when employed on vessels warning approaching or passing vessels the position and direction of movement of each other.

The invention consists in a suitable intermittently operated sounding device and a deflector or director associated therewith, which is adapted as the sounding device is operated to be rotated on a horizontal axis and deflect or direct the sound from one 25 direction to another, and after the sounding device ceases to operate to return to its normal position.

With the above mentioned and other objects in view—the invention consists in the 30 novel construction and combination of parts hereinafter described, illustrated in the accompanying drawings, and pointed out in the claims hereto appended; it being understood that various changes in the form, proportion, size and minor details of construction 35 within the scope of the appended claims may be resorted to without departing from the spirit or sacrificing any of the advantages of the invention.

To more fully comprehend the invention, reference is directed to the accompanying drawings, wherein is illustrated a preferred form of invention, and wherein—

Figure 1 is a view in side elevation of the 50 invention, disclosing the mechanism for intermittently operating the sounding device and the deflector. Fig. 2 is a top plan view of the device illustrated in Fig. 1, disclosing, in dotted lines, the location of the 55 sounding device.

Referring more particularly to the several views of the drawings, wherein like characters of reference designate corresponding parts throughout the several views, the numerals 1 indicate the side members of a suitable supporting frame connected together by suitable connecting bars 2. The frame is adapted to be positioned preferably on some elevated portion of the ship, where a comparatively unobstructed passage 60 may be had between the bow and stern of the vessel.

Rotatably mounted in journals 3, at one end of the side members 1, are the tubular and solid trunnions 4 and 5 of a suitable 65 parabolic deflector 6, and in the curvature of said deflector there is positioned a suitable sounding device, and for purposes of illustration I have shown the same in the form of a whistle 7 carried by a connection 8 extending through the tubular trunnion 4, and said connection is connected at its opposite end to a suitable source of fluid under pressure. A valve 9 positioned in the connection 8 and formed with an operating handle 70 10 controls the admittance of the fluid under pressure from the source of supply to the whistle.

A pinion 11 is mounted on the solid trunnion 5 and said pinion co-operates with a 75 rack 12 carried by the upper end of an arm 12' pivoted, as at 13, at its lower end to one of the side frame members. A link 14 is pivotally connected at one end to the arm 12' and is formed on its opposite end with 80 an elongated opening 14', in which is adapted to slide a headed crank pin, 14² projecting outwardly from the face of a disk 15 carried by a shaft 15' rotatably mounted in bearings 16 in the side frame members. The 85 inner face of the disk 15 carries a gear 17 which intermeshes with a pinion 18 carried at one end of the drive shaft 19 journaled in bearings 20 in the side frame members, and the drive shaft carries on its opposite 90 end a gear 21 which intermeshes with a power gear 22 operated in the direction of the arrow from any suitable source of power.

The peripheral edge of the disk 15 is provided with a raised or cam portion 23 and 105 coacting with the peripheral edge of the disk is the pin 24 carried by an arm 25 formed on one end of the shaft 26 journaled in bearings in the side frame members. The opposite end of the shaft 26 carries a crank 110

pin 27 at the end of an arm 28 secured to the shaft, and secured at one end to this crank pin 27 and connected at its opposite end to the operating handle 10, is a link 29 for controlling the opening and closing of the valve. A spring 30 normally maintains the valve 9 closed and the pin 24 in contact with the peripheral edge of the disk 14. Suitable arms 31 limit the movement of the deflector in either direction.

The apparatus being assembled and positioned as in the drawings, and the power gear being driven in the direction of the arrow, the same operates in the following manner:—The rotation of the disk 15 to a point where the raised or cam portion 23 contacts with the pin 24, forces the same rearwardly and causes the valve 9 to be opened, permitting a blast to be issued from the whistle 7. The blast of the whistle will be directed by the deflector 6 in one direction and will continue in that direction until such time as the pin 14² completes its idle movement in the slot 14' and contacts with the forward end thereof. As the pin 14² contacts with the forward end of the slot 14', it will cause the link 14 to be forced forwardly and raised at its slotted end, this action operating the rack 12 which will cause the deflector 6 to swing upwardly on its horizontal axis, and as the same passes over its center of rotation, it will fall by gravity in the opposite direction. Shortly after the deflector has been operated, as above described, the rotation of the disk 15 will cause the raised or cam portion 23 to complete its movement relative to the pin 24 and permit the spring to close the valve. The continued rotation of the disk 15 will cause the pin 14² to contact with the rear end of the slot 14' and cause the deflector to be oscillated to the position in full lines in the drawings, at which time the above stated cycle of operation will again take place.

By employing the device as above described, on vessels with the definitely arranged standard that the operation is to be from bow to stern, it will be apparent that the operators on one vessel hearing first a volume of sound which is gradually reduced, owing to being projected in an opposite direction, they will know that a vessel is approaching, and if there is heard first a volume of sound which is gradually increased, owing to being projected in a direction toward them, they will know that a vessel is receding from them; the difference in the volume of sound being the means whereby the relative direction of travel of the respective vessels is ascertained.

It is to be understood that the present invention may be employed at light houses and in place of the audible signal buoys now in use in form of buoys, and when so employed may be arranged in any stated man-

ner known to mariners, to project the sound parallel to the shore line or in the direction of the channel.

It will be apparent that the sounding device is in operation during but one movement of the deflector and remains silent during the return movement thereof, and the uniform variation of volume of sound will warn vessels of the direction of movement of each other.

Having thus described my invention what I claim as new and desire to protect by Letters Patent is:—

1. A signal comprising an intermittently operated movable sound deflector, a sounding device associated therewith, and means for operating said sounding device on the operation of said deflector in one direction only.

2. A signal comprising a movable sound deflector, a sounding device associated therewith, and means for intermittently operating said deflector and said sounding device, said sounding device being operated immediately before, after, and during the operation of said deflector in one direction.

3. In combination with a moving structure, a signal comprising a sound deflector pivotally mounted on a horizontal axis, a sounding device associated therewith, means for intermittently oscillating said deflector, and means for operating said sounding device immediately before, after, and during the oscillation of said deflector in one direction.

4. In combination with a moving structure, a signal comprising a parabolic sound deflector pivotally mounted on a horizontal axis, a sounding device positioned therein, means for intermittently oscillating said deflector, and means for operating said sounding device immediately before, after, and during the oscillation of said deflector in one direction.

5. In combination with a moving structure, a signal comprising a parabolic sound deflector pivotally mounted on a horizontal axis, a pressure operated sounding device positioned therein, continuously operated means for intermittently oscillating said deflector, and means operated by said deflector operating means for operating said sounding device immediately before, after, and during the oscillation of said deflector in one direction.

6. A signal comprising a sound deflector of substantially parabolic form supported for oscillation in a vertical plane, a sounding device positioned within the deflector, means for oscillating said deflector, and means for operating the sounding device.

7. A signal comprising a sound deflector of substantially parabolic form supported for oscillation in a vertical plane, a sounding device position within the deflector,

- means for oscillating said deflector, and means for continuously operating the sounding device on the oscillation of the deflector in one direction only.
- 5 8. A signal comprising a support, a sound deflector of substantially parabolic form, pivotally mounted on the support, the deflector having at one side a hollow trunnion engaging the support, a pressure operated sounding device positioned within the deflector, means for turning the deflector relative to the support, and means for operating
- 10

said sounding device including a pressure supply pipe extending through the said hollow trunnion and connecting with the sounding device. 15

In testimony whereof I have signed my name to this specification in the presence of two subscribing witnesses.

FREDERICK E. PERNOT.
